DESIGN FOR A SLIDE VIEWER

Percy H. Halbriter, Los Angeles, Calif.

Application December 10, 1946, Serial No. 135,397

Term of patent 7 years

(Cl. D57—1)

To all whom it may concern:

Be it known that I, Percy H. Halbriter, a citizen of the United States and resident of the city of Los Angeles, county of Los Angeles, State of California, have invented a new, original, and ornamental Design for a Slide Viewer, of which the following is a specification, reference being had to the accompanying drawings, forming a part thereof, in which:

Fig. 1 is a top plan view of a slide viewer, showing my new design;

Fig. 2 is a left end elevation;

Fig. 3 is a right end elevation; and

Fig. 4 is a side elevation thereof.

I claim:

The ornamental design for a slide viewer, substantially as shown.

PERCY H. HALBRITER.
